UNITED STATES PATENT OFFICE.

FRANK L. BUFF, OF EATON, ILLINOIS.

FLOOR-CLAMP.

No. 829,946.

Specification of Letters Patent.

Patented Sept. 4, 1906.

Application filed July 10, 1905. Serial No. 269,077.

To all whom it may concern:

Be it known that I, FRANK L. BUFF, a citizen of the United States, residing at Eaton, in the county of Crawford and State of Illinois, have invented a new and useful Floor-Clamp, of which the following is a specification.

This invention relates to devices for clamping and holding flooring, siding, weather-boarding, and the like while being nailed, and has for its object to improve the construction and increase the efficiency and utility of devices of this character.

With these and other objects in view, which will appear as the nature of the invention is better understood, the same consists in certain novel features of construction, as hereinafter fully described and claimed.

In the accompanying drawings, forming a part of this specification, and in which corresponding parts are denoted by like designating characters, is illustrated the preferred form of the embodiment of the invention capable of carrying the same into practical operation.

In the drawings, Figure 1 is a plan view of the improved device applied. Fig. 2 is a bottom plan view of the device. Fig. 3 is a sectional view on the line 3 3 of Fig. 1. Fig. 4 is a perspective view of the presser-foot detached. Fig. 5 is a perspective view of a modified form of presser-foot.

The improved device comprises a base member 10, having ribs 11 12 spaced apart for bearing upon opposite sides of a joist (represented at 13) and with the end opposite the ribs enlarged laterally, as at 14, and provided with a central aperture 15. The ribs 11 12 depend from the arm 10 and are disposed at right angles to the longitudinal plane of the arm, so that both edges of the arm are alike to provide for operating the device from the right or left, as hereinafter explained. Disposed upon the laterally-extended portions 14 of the base member is a cam 16, having an eccentrically-located stud 17 engaging the aperture 15 of the arm 10 and held rotatively therein by a clamp-screw 18. The cam member 16 is provided with an integral head-plate 19, overhanging the cam, and with an integral handle 20 extending from the head-plate. Surrounding the cam member is a cam-ring 21, supported in position by the lateral extension 14 and the plate portion 19 and provided with a radially-extending arm 22. Pivoted upon the free end of the arm 22

by a bolt 23 is a foot member 24, having a longitudinal channel 25 for engaging the "tongue" portion 26 of the flooring, (represented at 27.) The member 24 is also provided with spurs 28 to enter the body of the flooring 27 and prevent movement longitudinally of the flooring when the pressure is applied.

In operating the device the member 10 is placed over the joist 13 adjacent to the section of flooring 27 to be clamped and with the handle member set to move the cam 16 into its open or withdrawn position, or reversed to that shown in Figs. 1 and 2, which represents the parts in position after the completion of the clamping movement. The member 24 is then placed against the tongue 26 of the floor 27 and the member 10 adjusted to a point as near the floor as possible. Then as the handle 20 is operated the ribs 11 12 will bind tightly upon the joist 13, while the cam member 16 will force the foot member 24 with great force against the floor member 27 through its action upon the ring 21 and arm 22, and thus effectually close any open joint which may occur between the flooring being directly acted upon and the next floor member and likewise correct any irregularities in the shape of the floor members.

The same device may be employed for clamping and holding siding and weather-boarding by substituting a foot member with one side wall of the channel portion wanting to adapt the foot member to the form of the tongue on material of this character, which is usually at one side.

The arm 10 being rotatable upon the stud 15 and the lever 20 being also rotatable upon the member 21, the two members 10 and 20 can be quickly transposed to reverse the implement and transform it from a right to left hand implement. This is of material advantage in certain localities—as, for instance, at the right-hand end of the floor or wall the lever 20 and grip-arm 10 will be disposed in one position and may thus be employed at each joist across the building; but when the opposite wall is reached the implement cannot be applied to the floor or siding at the left end unless the arm and lever are transposed. This is an important advantage and adds materially to the value and efficiency of the implement.

The device is simple in construction, being formed of four pieces only besides the two bolts 18 and 23.

The ribs 11 12 on the member 10 are spaced a little greater distance apart than the width of the joist 13, which vary from 2 to 6 inches or more, and a plurality of the members 10 of 5 varying sizes, or with gripping members spaced at different distances, may be furnished with each of the cam and handle members, which may be readily attached by merely removing the one screw member 18.

10 The two forms of the foot members 24 to fit different forms of material may be furnished with each device and readily attached by simply detaching the one bolt 23.

15 Having thus described the invention, what is claimed is—

In a device of the class described a grip-arm having spaced transverse ribs depending therefrom and disposed at right angles to the

longitudinal plane of the same, a lever pivoted to said grip-arm and provided with a cam-plate eccentric to said pivot, an annular member rotatively engaging said cam-plate and provided with a radial arm, and a presser-foot swinging from the free end of said radial arm, said grip-arm and lever 20 adapted to be transposed in position relative to said annular member and its arm and presser-foot.

In testimony that I claim the foregoing as my own I have hereto affixed my signature in 25 the presence of two witnesses.

FRANK L. BUFF.
